LIQUID COOLER CONTROL

Dewey H. Dolison, Mount Vernon, Ohio

Application September 12, 1935, Serial No. 40,238

10 Claims. (Cl. 62—7)

This invention relates to liquid coolers, and more particularly to an improved method and apparatus for controlling the flow of the refrigerating medium. In liquid dispensing, particularly of carbonated beverages such as beer, it is necessary to have a control flexible enough to serve drinks cold occasionally or continuously. Up to the present, difficulty has been experienced in such systems in obtaining such flexibility of performance. If the control is set to maintain a steady cold flow of liquid, then at light loads there is apt to be serious frostbacks and even freezing of the beverage. On the other hand if the control is set for light loads, a heavy continuous flow of beverage will result in such a severe overload as to prevent proper refrigeration. Reliance is placed upon the cessation of beverage flow between successive glasses to obtain proper refrigeration in the cooling coil. But it frequently happens that a large container of beverage is drawn or even successive glasses without any interruption to the flow. In such a case, the difficulties mentioned above militate against satisfactory performance of a direct expansion system.

An object of this invention is to devise a liquid cooler control for a direct expansion system which will obviate the above difficulties and will permit the cooling coil to supply a continuous flow or an occasional dribble of beverage properly refrigerated.

A further object is to devise a liquid cooler coil and control which will be flexible enough to function satisfactorily from no load to full load continuous operation in a direct expansion system.

An additional object is to devise a liquid cooler and control which will be simple, cheap, positive in operation and capable of use with different sizes of installations.

An additional object is to devise a liquid cooler control which is responsive to one or more beverage temperatures and to supply as much refrigeration as the load demands.

Other and additional objects will become apparent as the description proceeds.

Referring to the drawing,

Fig. 1 shows a complete liquid cooler system with my control applied thereto.

Figs. 2 to 5 inclusive show modified forms of liquid cooler coils and control.

Referring to Fig. 1, an electric motor 1 is connected by a belt 2 to a compressor 3. Compressed refrigerant is delivered through pipe 4 and condensed in a receiver 5. Liquefied refrigerant is delivered by a pipe 6 from receiver 5

to a control valve 7 to be later described in detail. Valve 7 is provided with an outlet 8 which is adapted to feed liquefied refrigerant through a pipe 9 to a liquid cooling conduit or coil 10.

Cooling conduit or coil 10 comprises a plurality of nested conduits such as an inner pipe 11 adapted to have any beverage therein and a surrounding telescoped pipe 12 adapted to contain the refrigerant. Supply pipe 9 leads to a suitable fitting 15 at one end of the conduit or coil 10 permitting refrigerant to flow into outer pipe 12 and permitting beverage pipe 11 to extend beyond coil 10. Coil 10 is extended for any suitable length and may be coiled, as shown, or straight or disposed in any desirable manner. It 15 may for example be the connecting pipe between beer kegs in a cellar and faucets in a bar fixture. The other end of coil 10 terminates in a fitting 16 similar to 15. From fitting 16 a pipe 17 conducts the volatilized refrigerant to a back pressure valve 18 and thence by suction line 19 back to compressor 3. Valve 18 functions as a valve to maintain a suitable pressure in the cooler coil. Such pressure would be substantially equivalent to that at which the particular refrigerant employed in 25 the system boils when the temperature thereof is about that to which it is desired to cool the beverage in pipe 11.

The entire refrigerating system is provided with the customary low pressure control comprising a 30 pipe 20 leading from suction line 19 to a pressure control switch 21 set to operate between two pressure limits. Inasmuch as such control systems are old, no further description is necessary. When enough refrigerant in the entire system 35 has volatilized to raise the pressure in suction line 19 to the critical value, motor 1 is switched in and the compressor is driven. Finally when sufficient refrigerant has been transferred from the suction line to the receiver and liquefied to 40 reduce the pressure in suction line 19 to the critical value, then the motor stops. This control however is supervisory only and does not function to control the amount of refrigeration applied to the beverage. This control is merely to insure 45 a reservoir of liquefied refrigerant upon which the cooling coil and its own control can operate.

It will be noted that the beverage in pipe 11 comes in at fitting 16 and its flow is counter to that of the refrigerant through the cooling conduit. At a point on coil 10 well toward the end of the coil as measured in the direction of refrigerant flow, I dispose a receptacle or bulb 25. This bulb or receptacle is a sleeve over inner pipe 11 and within outer pipe 12. This sleeve has its 55

ends 26 and 27 crimped down to pipe 11 and suitably soldered thereto to form a gas tight chamber. A pipe or capillary tube 28 leads from bulb 25 to valve 7 through cover plate 30. This cover plate 5 with a flexible diaphragm 31 forms an expansible chamber 32 in gaseous communication with bulb 25. A suitable expansible fluid such as methyl chloride may be disposed within bulb 25.

Cover plate 30 is attached to valve body 33. 10 Within valve body 33 is a push rod 34 attached to a head 35 disposed in proximity to diaphragm 31. The bottom of rod 34 rests upon a ball valve 36 pressed upwardly against its seat 37 by a spring 38 and cup-shaped retainer 39. Pipe 6 15 communicates with chamber 40 within the lower part 41 of the valve body while pipe 9 communicates with the outlet portion of valve 7. Upon expansion of gas within bulb 25 and chamber 32, diaphragm 31 is sprung downwardly to force ball 36 away from its seat and open valve 7. Refrigerant in liquid form and under pressure is thereupon forced into cooler coil 10. While I have described valve 7 in detail, it is understood of course that any other suitable valve mechanism may be used.

Assuming receiver 5 has sufficient refrigerant in liquid form therein, coil or conduit 10 will operate as follows: Under no load conditions, the column of beverage will be at a temperature of 30 approximately 45° F. for example. Under these conditions, conduit 10 will have a portion thereof filled with liquefied refrigerant to a point near the receptacle or bulb 25. If a glass of beverage is drawn, the entire beverage liquid column will 35 advance in inner pipe 11 downward as seen in Fig. 1. Some warm beverage will come into contact with bulb 25 and cause the pressure therein to increase. This will result in valve 7 opening and permit liquid refrigerant to rush into outer 40 pipe 12. Liquid refrigerant will advance to contact the receptacle or bulb 25 which will be chilled and valve 7 closed. The liquid refrigerant will gradually recede or be forced back by vaporization thereof effected through the absorption of heat. As long as the temperature of 45 the receptacle or bulb 25 is substantially equal to the temperature of the liquefied refrigerant, nothing will happen. As soon, however, as the temperature of the bulb 25 rises above the pressure temperature value, which value is determined by the setting of back pressure valve 18, then valve 7 will be opened. This rise in temperature of the bulb 25 and thermally responsive fluid or vapor contained therein may be due to 50 heat leak or warm beverage flowing in the conduit 10 or both. If a heavy draught of beverage is taken off, a correspondingly heavy charge of refrigerant will be introduced into the conduit or coil 10. By proper design it is possible to 55 have a continuous flow of beverage and a continuous flow of refrigerant which is substantially completely evaporated before reaching bulb 25. The length of the conduit or coil 10 from bulb 25 to fitting 16 is in the nature of a drying coil 60 to insure against frost back on line 17 under extreme conditions.

There is always a column of refrigerated beverage in the conduit or coil 10 ready for instant use and this column will always remain cold.

70 In practice, the coil 10 may be severed at the bulb center and the parts built up and soldered in place.

In Fig. 2, bulb or receptacle 225 is shown on the outside of the coil. Within bulb 225, is a pipe 75 212 for refrigerant and within that is a pipe 211

for beverage. This construction may be used where the beverage, as beer, is stored in a refrigerated container and its temperature effect on bulb 225 is unnecessary. In such a case, bulb 225 is responsive only to the refrigerant medium 5 directly. Indirectly of course, beverage in pipe 211, if warm, will cause refrigerant to vaporize in that region and warm up the receptacle or bulb 225. Such a construction is cheaper than that disclosed in Fig. 1 and may advantageously be used in certain cases.

Fig. 3 shows outer pipe 312 for refrigerant enclosing bulb 325 as in Fig. 1. Within bulb 325, however, are two pipes 310 and 311 for beverages. In this case, bulb 325 will respond to 15 the warmest of the two beverages. Along the length of the entire coil, the temperature of the two beverages will be equalized so that if one is drawn heavily and the other lightly, the lightly drawn beverage column will tend to cool the 20 other beverage column.

In Fig. 4 an outer pipe 430 is provided for one beverage. Within that is a refrigerant pipe 431. Inside of pipe 431, is bulb 425 with one side touching pipe 431. Within bulb 425 is a second 25 beverage pipe 432. By having bulb 425 in intimate contact along one side with 431 at point 433, bulb 425 is made more responsive to conditions in the outer beverage line 430. Conditions within beverage line 432 will affect bulb 425 in- 30 directly as in Fig. 2.

Fig. 5 is similar to Fig. 3 except that the two beverage pipes 510 and 511 are separate pipes instead of one having a dividing wall. Otherwise refrigerant line 512 and bulb 525 function 35 as in Fig. 3.

It will further be noted that in all the figures, the beverage conduit presents a smooth and unbroken surface to the beverage flow. This is important for several reasons. Since many beverages are carbonated, there is a tendency for 40 gas to bubble out at sharp corners and projections and cause excessive foaming. Then in cleaning, a cleaning solution will function more effectively along a smooth surface.

The present invention provides a novel control for beverage cooling systems and the like in which the cooling of the liquid is effected by direct heat interchange from a volatile refrigerant to the liquid to be cooled. The positioning 50 of the bulb or receptacle 25 containing the expansible fluid which governs the refrigerant inlet valve so that the expansible liquid is subjected predominantly to only the heating or cooling effects of the liquid to be cooled and the 55 refrigerant, promotes a rapid response of the refrigerant inlet valve to a demand for refrigerant. A body of the fluid which is responsive to temperature changes is thus housed in a receptacle having one wall positioned to be traversed by substantially all of the refrigerant flowing through the refrigerant passageway and having another wall to be traversed by substantially all of the liquid flowing through the liquid passageway. In this manner the body of thermally 60 responsive fluid is subjected substantially solely to the temperatures of the liquid being cooled and the refrigerant to cool the liquid while the said liquid and refrigerant are flowing through their respective courses. Heating sources or 65 cooling effects outside of the cooling conduit do not directly influence the expansible fluid in the thermostatic receptacle. Such effect as outside heat or cold has on the control of the inlet valve is transmitted indirectly to the receptacle or bulb 75

25 through the passageway in the cooling conduit which surrounds the bulb.

Liquid-cooling devices constructed in accordance with the present invention exhibit remarkably close control of the temperature of the cooled liquid discharged. On account of the extreme sensitiveness of the novel thermostatic device for controlling the admission of refrigerant to the cooling conduit there is avoidance 10 of lag or delay in the supplying of fresh quantities of liquid refrigerant to cool a sudden or continued influx of warm liquid.

Other means of utilizing the principles of the present invention are contemplated, change being made in the particular details of procedure and construction set forth as required, it being understood that the embodiments shown are given for purposes of explanation and illustration.

20 Having described the invention, what is claimed is:

1. A liquid cooler comprising an outer conduit having an inlet end and an outlet end, pipe means arranged within said conduit and extending 25 through the same substantially from end to end and having outlet means at the inlet end of said conduit, and a thermostatic control device arranged within said conduit; said device comprising a sleeve substantially enveloping a portion of 30 said pipe means and cooperating therewith to form a fluidtight chamber having one wall subjected to the temperature of fluid passing through said conduit, and a capillary tube communicating with the interior of said chamber and passing 35 through said conduit to the exterior thereof.

2. A liquid cooler, comprising a conduit having a plurality of passageways extending in parallelism therethrough, one of said passageways arranged to carry a refrigerant and another passageway arranged to carry a liquid to be cooled, a pressure valve to regulate the withdrawal of refrigerant from the conduit and maintain a predetermined pressure in the refrigerant passageway, an inlet valve associated with the refrigerant passageway to regulate the admission of refrigerant thereto, and means responsive to temperature changes to open and close the inlet valve, said means including a receptacle positioned for direct heat exchange with the passageways and intermediate the ends of the conduit, said receptacle being located within the said conduit in position to be traversed by substantially all of the refrigerant flowing through said refrigerant passageway and by substantially all of the liquid flowing through the second mentioned passageway.

3. A liquid cooler, comprising a conduit having a plurality of passageways therethrough, one of said passageways arranged to carry a refrigerant 60 in a generally ascending direction, and another passageway arranged to carry a liquid to be cooled in a direction opposite to the direction of flow of the refrigerant, a pressure valve to regulate the withdrawal of refrigerant from the conduit and maintain a predetermined pressure in the refrigerant passageway, an inlet valve associated with the refrigerant passageway to regulate the admission of refrigerant thereto, and means responsive to temperature changes to open and close the inlet valve, said means including a receptacle positioned for direct heat exchange with the passageways and intermediate the ends of the conduit, said receptacle being located within the said conduit in position to be traversed by substantially all of the refrigerant flowing through said

refrigerant passageway and by substantially all of the liquid flowing through the second mentioned passageway.

4. A liquid cooler, comprising a conduit having a plurality of passageways extending in parallelism therethrough, one of said passageways arranged to carry a refrigerant and another passageway arranged to carry a liquid to be cooled, each of said passageways having an inlet end and an outlet end, the inlet end of the refrigerant passageway being positioned adjacent the outlet end of the liquid passageway and the inlet end of the liquid passageway positioned adjacent the outlet end of the refrigerant passageway, a pressure valve to regulate the withdrawal of refrigerant from the conduit and maintain a predetermined pressure in the refrigerant passageway, an inlet valve associated with the refrigerant passageway to regulate the admission of refrigerant thereto, and means responsive to temperature changes to open and close the inlet valve, said means including a receptacle positioned for direct heat exchange with the passageways and intermediate the ends of the conduit, said receptacle being located within the said conduit in position to be traversed by substantially all of the refrigerant flowing through said refrigerant passageway and by substantially all of the liquid flowing through the second mentioned passageway.

5. A liquid cooler, comprising a conduit and one or more parallel pipes passing through the interior of said conduit and cooperating therewith to form passageways extending longitudinally through the conduit, an inlet valve to regulate the admission of liquid refrigerant to one of the passageways, means to control the operation of said valve, said means including a receptacle located within said conduit in position to be subjected directly to temperature changes in each of the passageways at a region intermediate the ends of the conduit, and a pressure valve to regulate the withdrawal of refrigerant from the refrigerant passageway, said pressure valve arranged to permit the flow of refrigerant out of the refrigerant passageway when the pressure therein exceeds a predetermined value and to prevent such flow when the pressure therein is less than a predetermined value

6. A liquid cooler comprising a plurality of passageways extending in substantially side by side parallel relation, one of said passageways having an inlet and an outlet and arranged to carry a volatile refrigerant, another of said passageways arranged to carry a liquid, means for supplying refrigerant to the refrigerant passageway, a pressure valve to regulate the withdrawal of refrigerant from the refrigerant passageway and maintain a substantially uniform predetermined pressure therein, an inlet valve associated with the inlet end of the refrigerant passageway to regulate the admission of liquid refrigerant, and means responsive to temperature changes to open and close the inlet valve, said means including a receptacle for an expandible fluid positioned between the passageways and having one wall in common with the refrigerant passageway to be traversed by substantially all of the refrigerant flowing through the refrigerant passageway, and another wall in common with the liquid passageway to be traversed by substantially all the liquid flowing through the said liquid passageway, and the receptacle arranged to be alternately subjected to substantially predominantly liquid refrigerant and to substantially predominantly gaseous refrigerant as the effective level of liquid

refrigerant advances and recedes in the refrigerant passageway.

7. The method of cooling a liquid which comprises passing the liquid over a course traversing one side of a body of fluid responsive to temperature changes, passing a volatile refrigerant over a course paralleling the course of the liquid to be cooled and in direct heat-exchanging relation therewith and over another side of the said body of fluid, maintaining a substantially constant pressure on the refrigerant in the refrigerant course, subjecting said body of fluid solely to the temperatures of said liquid and said refrigerant in said courses, and controlling the admission of refrigerant to the refrigerant course solely in response to changes in temperature of said body of fluid.

8. The method of cooling a liquid which comprises passing the liquid over a course traversing one side of a body of fluid responsive to temperature changes, passing a volatile refrigerant first over a course paralleling the course of the liquid to be cooled and in substantially direct heat-exchanging relation therewith and then over another side of the said body of fluid, maintaining a substantially constant pressure on the refrigerant in the refrigerant course throughout substantially the entire length thereof, subjecting said body of fluid solely to the temperatures of said liquid and said refrigerant in said courses, and controlling the admission of refrigerant to the refrigerant course solely in response to changes in temperature of said body of fluid.

9. The method of cooling a liquid which com-

prises passing the liquid over a course which first traverses a body of fluid responsive to temperature changes and then parallels a refrigerant course, passing a volatile refrigerant over a course which first parallels the liquid course in heat-exchanging relation therewith and then traverses another side of said body of fluid, maintaining a substantially constant pressure on the refrigerant in the refrigerant course throughout substantially the entire length thereof, subjecting said body of fluid solely to the temperatures of said liquid and said refrigerant in said courses, and controlling the admission of refrigerant to the refrigerant course solely in response to changes in temperature of said body of fluid.

10. The method of cooling a liquid which comprises passing the liquid over a generally descending course which first traverses a body of fluid responsive to temperature changes and then parallels a refrigerant course, passing a volatile refrigerant in a generally ascending direction over a course which first parallels the said liquid course in heat-exchanging relation therewith and then traverses another side of the said body of fluid, maintaining a substantially constant pressure on the refrigerant in the refrigerant course throughout substantially the entire length thereof, subjecting said body of fluid solely to the temperatures of said liquid and said refrigerant in said courses, and controlling the admission of refrigerant to the refrigerant course solely in response to changes in temperature of said body of fluid.
